Sketch July 8, 1851.

Original No 393

Furniture for Drawing Room

James N. DeWitt, Buffalo, N.Y.
Letters Patent No 393. Dated July 8th 1851

The Schedule referred to in these Letters Patent and making part of the same.

To all whom it may concern

Be it known that I James N. DeWitt of Buffalo in the County of Erie and State of New York have invented a new and useful form or Design for Stoves, of which the following, description is illustrated by the accompanying drawings, references ^{and} are sufficiently clear and comprehensive to enable others of competent skill to make and use my invention.

A. is the form of the design upon the front door of the fire place - B. the figure upon the door at the end of the fire chamber and C. bearing some resemblance to A is the design upon the door of the oven situated beneath the fire place and D. is the design upon the door of the other oven situated back of the first.

Each of the said doors and the side plates of the stove are surrounded by a plain border as shown in the drawing (The figures upon opposite sides of the stove are similar.

What I claim as new and desire to secure by Letters Patent is the design and configuration of ornamental stove plates as herein described and represented in the annexed drawings
